TELEPHONE SYSTEM

Reginald Taylor, Liverpool, England, and George Thomas Baker, Caerphilly, Wales, assignors to Associated Telephone and Telegraph Company, Chicago, Ill., a corporation of Delaware

Application November 22, 1934, Serial No. 754,250
In Great Britain December 6, 1933

8 Claims. (Cl. 179—18)

The present invention relates to telephone systems and has for its main object the provision of improved automatic switching apparatus for use in such systems for increasing the rapidity and reliability with which connections may be set up automatically. Another object of the invention is to provide improved methods of testing for the various conditions which arise during the operation of the automatic equipment.

10 According to one feature of the invention, a potential operated device such as a thermionic vacuum tube or a grid controlled gas discharge tube is employed for indicating when a particular condition exists in all of a group of pieces of apparatus. Thus it may be used for operating a relay to perform a switching operation when all of a group of pieces of switching equipment become busy. This feature of the invention is of general application wherever it is desired to respond to a change in potential on a lead without connecting potential to the lead from the responding device.

Other features of the invention, however, are concerned more particularly with telephone systems employing finder switches, and from this point of view the invention may be considered as an improvement in the system described in U. S. Patent No. 1,914,540. In this prior arrangement the primary finder switches were arranged so that those first taken into use are directly connected to first group selector switches, while those last taken into use were arranged to be connected to group selector switches in a common group over secondary finder switches. The primary finder switches were of the two-directional type provided with vertical and rotary magnets for effecting the setting of the switches and with a release magnet for allowing the switch to restore to normal.

40 One of the features of the present invention relates to improved circuit arrangements, whereby the primary finder switches may be of the two-directional type in which no release magnet is provided, the restoration of the switch to normal being effected by the intermittent operation of one of the magnets employed for setting the switch so that the switch wipers in the complete setting and restoration operation perform a rectangular movement.

50 Another feature of the invention relates to arrangements whereby the time required in setting up the connection may be decreased by causing the various switches to move at an increased speed. The increased speed of stepping is achieved 55 by employing self-interrupted stepping circuits

to the magnets of the various switches, together with other circuit modifications which are necessary in order that the switches shall still operate accurately at the higher speed.

The invention will be better understood from the following description of one method of carrying it into effect, reference being had to the accompanying drawings comprising Figs. 1 to 10; Figs. 1 to 9 should be arranged as shown in Fig. 10 to form a complete circuit.

Fig. 1 shows a subscriber's line circuit and also the start relays SA, SB, SC, SD and SE which are common to a group of 200 lines; Figures 2 and 3 show a primary finder circuit which is the same for both regular and overflow primary finders. Figure 5 shows the group busy detecting circuit for the regular and overflow groups of finders comprising respectively the thermionic valves VAA and VAB. The start circuits to the primary control sets PC1, PC2 and PC3 are also shown. Figures 6, 7 and 8 show primary control set PC1, which is associated with regular and overflow finders over the distributor switches RPD and OPD respectively; Figure 9 shows one of the secondary start groups SS1 which controls two secondary control groups such as SC1 each having access to a group of secondary finders over a secondary distributor such as SED. Figure 4 shows one of the secondary finders SFS which has access over the connections on the distributing frame IDF to finders in the overflow primary group.

Referring now to the assembled circuit, it should be explained that the necessary changes of connection according to the conditions under which the finders are to be used are made at the intermediate distributing frame IDF shown in Fig. 4, and in this instance the broken line connections shown are suitable for regular finders which are directly connected to first group selectors, while the connections shown in broken lines intercepted by dots apply to overflow finders, in which case connection with a first group selector is made by way of a secondary finder. The same convention is employed in connection with leads 23 and 28 in the upper right-hand corner of Fig. 5. For the purpose of the first part of this description it will be assumed that the finder shown is one of a regular group, and accordingly the broken line connections only will apply.

Referring now to Fig. 1 of the assembled circuit, when the calling subscriber removes his receiver to originate a call, a circuit is completed by way of his instrument circuit over conduct-

tors 10 and 11 to operate the line relay L over both its windings in series in circuit with the resting armatures k2 and k3. Relay L at armature l1 marks the rotary bank of all finders with 5 battery extended through the winding of relay K shunted by a comparatively low resistance 12, and at armature l2 extends battery by way of a resistance such as YA (provided one per calling level) to mark in the vertical bank multiple the 10 level in which the calling line is situated. It will be seen from the drawings that the vertical bank VB Fig. 2 extends to five relays, viz: SA, SB, SC, SD and SE which are provided with two windings each, one per level, and these relays are 15 arranged to be operated from the marking battery extended by armature l2 to complete a start circuit for one or other of the primary control sets such as PC1 (shown in Figs. 6, 7 and 8) having access by way of a distributor switch or 20 switches to all finders in the group.

As fully described in the prior patent referred to, these relays are provided for the purpose of starting up the primary control sets PC1, PC2 and PC3, either separately or together, depending 25 upon the calling conditions at any particular instance. Arrangements are also shown for altering the connections between the armatures of these relays according as two or three primary control sets are provided. In the present case 30 three primary control sets are assumed to be fitted and accordingly connection is made between the terminal points U26, U28 and U30, U32 as shown. If only two primary control sets are provided the terminal U32 will obviously be 35 spare and connection is then made between terminal points U24, U26 and U28, U30.

For the purposes of this description it will be assumed that relay SA is the one which is energized in parallel with the marking battery to the 40 vertical bank VB and at armature sa1 located in the bottom left-hand corner of Fig. 5 a circuit is completed for the start relay ST of primary control set PC1 which may be traced from earth at armature sa1, armature of23, conductor 13, armature rs2, left-hand winding of relay ST to battery by way of resistance YC. Relay ST in operating at armatures st5, st6 and st7 prepares a 45 circuit for a delayed alarm changeover device comprising the relays TA, TB and TC which will 50 be described later, and at armature st1 (Fig. 7) completes the following circuit for energizing relay LK providing that the regular primary distributor switch RPD has already preselected an idle regular finder: earth at operated armature 55 st1, comparatively low resistance 14, windings of relay LK in series, armatures tb5, dv3, tc2, rs5, ofr3, wiper R1 and bank contact of switch RPD, conductor 15, off-normal springs N1 of the pre-selected finder, armature ha1 jumper connection 60 at distributing frame IDF, release trunk conductor P of the associated selector to idle marking battery therein. It should be mentioned that the preselecting circuit of the regular primary distributor switch RPD functions in the following 65 manner. If the finder engaged by the distributor is busy, wiper R1 will encounter earth connected over operated springs N1 via the low resistance right-hand winding of relay HB and relay G thereupon operates over the following 70 circuit: earth on wiper R1, armatures ofr3, rs5, tc2, dv3, tb5, windings of relay LK in series, resistance 14, armatures lk1 and vr2, interrupter springs rpm1 and opm1, conductor 17, winding of relay G, conductor 16, armature of24 to battery 75 by way of resistance YA. Owing to its high

resistance, relay G alone is operated in this circuit and at armature g1 energizes the driving magnet RPM of the regular primary distributor, in a circuit including normally operated armature rf2 (Fig. 5). The magnet in energizing 5 prepares for the advancement of the wipers R1 to R8 into engagement with the next set of bank contacts and at the conclusion of its stroke operates the associated interrupter springs rpm1, thereupon opening the circuit to relay G which 10 releases. In this manner, interaction takes place between relay G and the magnet RPM so that the wipers will be automatically rotated until the first idle finder is encountered.

In order to obviate the possibility of incorrect 15 operation owing to a disconnection in the bank engaged by wiper R1 it is arranged that when a call is initiated a test is made over this wiper for idle marking battery and if no such battery is encountered, relay LK will fail to operate and 20 the following self-interrupted driving circuit becomes effective to magnet RPM to advance the wipers on to the next set of contacts: earth at armature st1 (Fig. 7) armatures lk1 and vr2, interrupter springs rpm1 and opm1, conductor 25 17, armatures st2, ofr2 and rf2, winding of magnet RPM to battery. Automatic rotation therefore takes place and when idle battery is found, relay LK operates over the circuit previously described and opens the circuit of magnet RPM at 30 the resting contacts of armature lk1, while at the make contacts of this armature a circuit is completed to the upper holding winding of relay LK which is sufficiently low in resistance to mark 35 the selected finder as busy in the bank of the distributor switch. The operation of armature lk1 also removes a shunt from relay VR which extends from its right-hand terminal over armature dv1, resistance 14, armatures lk1 and vr2, interrupter springs rpm1 and opm1, conductor 40 17, armatures st2, ofr2, rf2, ofc2 and st3 to its left-hand terminal. Relay VR thereupon operates in series with the lower winding of relay LK shunted by resistance 14 to battery in series with the driving magnet RPM. Due to the reversal 45 of current flow in its lower winding the two windings of relay LK are now in opposition and the lower winding partly neutralizes the flux produced by the upper winding, although the resultant flux under the conditions prescribed is 50 quite sufficient to hold the relay operated.

If, however, two distributor switches engage 55 the same finder simultaneously, both relays LK in the respective control sets will operate although one may operate somewhat before the other due to slight differences which must always be present even between such similar relays. Consequently, with two distributors testing on to the same finder the current in the holding winding of each LK relay will be approximately 60 half the normal holding current so that the opposing lower winding will now almost completely neutralize the effect of the upper winding and the relays will start to release. Again due to 65 inherent differences in the relays one will start to release first, and immediately it opens its make contacts it will restore almost full holding current to the other relay which then alone remains operated. In order that the relays VR shall not operate during the testing period described, they 70 are preferably made slow to operate by providing them with highly inductive windings which in addition are normally shunted by a resistance, and by suitable choice of values a safe period for testing can be ensured.

When relay VR operates, it locks over its armature *vr1* to battery in series with the driving magnet RPM, at armature *vr4* operates relay SF (Fig. 8) in series with one winding of the line 5 relay of the associated group selector (not shown) at armature *vr5* connects earth to wiper *R6* of the distributor to operate relay HA in the finder, at armature *vr6* (Fig. 7) connects relay LK in circuit with the vertical bank VB of the finder, 10 at armature *vr7* (Fig. 6) connects earth to a common conductor 18 to ensure that the common relay OFZ (Fig. 5) shall not operate at this time. Relay SF in operating prepares the circuit to the cut-off relay CO (Fig. 8) which is normally 15 short-circuited by way of the armatures *pb1* and *pa1* of the wiper testing relays PA and PB. The operation of relay HA in the finder at armatures *ha1* disconnects idle marking battery from bank R1 to busy the finder and as a result relay LK in 20 the control set releases and at the resting contacts of its armature *lk1* completes a circuit for operating relay DV over its left-hand winding. Relay DV in operating at armature *dv1* completes a testing circuit for relay LK, this time in circuit 25 with the right-hand winding of relay DV and at armature *dv2* extends earth from armatures *st1* and *lk1* to wiper *R3* to complete a self-interrupted driving circuit to the vertical magnet VM of the finder. Intermittent energization of the magnet VM which is brought about by the self-interrupting contacts *vm1*, results in the shaft 30 and wipers of the finder being raised to the marked level; when this is reached the vertical wiper VW picks up idle marking battery which is extended over wiper and bank R2 of the distributor switch to operate relay LK over both its windings in series. Relay LK thereupon at armature *lk1* opens the driving circuit to the vertical magnet and completes a holding circuit 35 over its upper winding which is sufficiently low in resistance to guard the selected level. Simultaneously with this operation relay LK completes a circuit to its lower opposition winding in series with the right-hand winding of relay DV and the 40 dual testing operations already described are again performed in connection with the vertical bank. It will be noticed that the right-hand winding of relay DV is shunted by a resistance, the value of this resistance is suitably chosen in relation to the winding resistance so 45 that the combined resistance presented to relay LK is the same as that presented when relay VR was connected in circuit.

Assuming that no other finder is testing on the 50 same level at this instance, relay LK will hold in spite of the opposition winding and at armature *lk2* (Fig. 6) complete a circuit for operating relay RS (Fig. 8) over its lower winding, armature *dv4* and conductor 24, in series with the 55 right-hand winding of the start relay ST (Fig. 6) to battery by way of the driving magnet RPM. Owing to the high resistance of this circuit the driving magnet RPM does not function. Relay RS in operating locks over its upper winding at armature *rs2* transfers the initial energizing circuit of relay ST to the control of armature *lk2*, at armature *rs3* (Fig. 8) maintains relay HA in the 60 finder, at armature *rs4* opens the initial energizing circuit to relay DV which however, remains held over its high resistance right-hand winding in series with the vertical magnet VM, at armature *rs5* connects battery via resistance YB to wiper *R1* of the distributor switch to operate 65 relay HB in the finder. Relay HB in operating 70

at armature *hb3* disconnects battery from the holding circuit of relay DV in the control set which thereupon releases and completes the following self-interrupted driving circuit to the rotary magnet RM; earth at armature *tc5* (Fig. 8) 5 armatures *rs6*, *pa1*, *pb1*, conductor 19, armatures *dv6*, *ofc4*, wiper *R8* and bank contact, conductor 20, interrupter springs *rm1*, winding of rotary magnet RM to battery. Intermittent energization of the rotary magnet RM brought 10 about due to the interrupter contacts *rm1* results in the wipers of the finder being rotated in search of the calling line which may be in either the P1 or P2 bank, depending upon whether the subscriber is located in the "odd" or "even" hundred 15 line group.

If the subscriber is in the "odd" group, the test wiper P1 (Fig. 2) will encounter the marking battery when the calling line is reached and this is extended by way of the wiper and bank R3 of the distributor (Fig. 7) to operate the test relay PA in the control set. 20

If, however, the subscriber is located in the "even" group test wiper P2 will pick up the marking battery which is extended by way of wiper R5 to operate the other test relay PB (Fig. 8). The operation of either testing relay is arranged to open the operating circuit to the rotary magnet and thereby hold the wipers in engagement 25 with the calling line. 30

If it is assumed that relay PA is the one which is operated, then armature *pa1* (Fig. 8) opens the driving circuit to the rotary magnet and completes a holding circuit for relay PA over its lower winding in series with the right-hand winding of the start relay ST to battery by way of the driving magnet RPM, and armature *pa2* connects earth to wiper *R6* of the distributor to hold the switching relay HA in the finder. The operation of armature *pa1* also removes a 35 short-circuit from the cut-off relay CO (Fig. 8) which is of comparatively high resistance and thereupon immediately operates in series with the rotary magnet RM of the finder. Relay CO at armature *co1* completes a locking circuit for 40 itself by way of the comparatively high resistance YD, at armature *co3* maintains relay SF on its upper winding, at armatures *co4* and *co5* short-circuits the upper windings of relays PB and PA respectively, and at armatures *co6* and *co7* short-circuits both windings of the start relay ST which 45 releases. Relay ST thereupon releases relays LK, VR and relay LK releases relay RS; upon the release of the latter relay earth is disconnected from one terminal and connected to the other terminal of the lower holding windings of relays PA and PB at armature *rs6*. Relay PA which was holding to battery from the driving magnet RPM thereupon releases and the magnet becomes 50 fully operated to kick the wipers of the distributor off the now busy finder when the operating circuit is opened. Upon the release of relay PA a short-circuit is again connected across relay CO so that it too releases and in turn releases relay SF; under this condition the resistance YD limits 55 the current in the circuit of the rotary magnet in the finder to prevent its further operation. All relays in the control set are now restored to normal and upon the opening of the circuit of the driving magnet RPM at armature *co2* the magnet de-energizes and the wipers of the distributor switch are automatically advanced on to 60 the next set of contacts.

Relay K in the calling subscriber's line circuit operates in series with the test relay in the 65 70 75

control set and when the control set releases it locks in series with the switching relay in the finder over a circuit which may be traced as follows: battery via the winding of relay K, operated armature $k1$, release trunk conductor P, bank and wiper $P1$ of the finder, armatures $ha3$ and $hb3$, springs $NR1$, conductor 21, upper low-resistance winding of relay HA, conductor P to earth connected up at the controlling switch 10 in the train. Relay K also at armatures $k2$ and $k3$ clears the calling circuit of its battery and earth connections, whereupon relay L releases after its slow period and opens the marking circuit and the start circuit to the primary contact 15 trol sets. It will be noticed that upon the release of armature $l1$, relay K is again connected to the private normal conductor extending to the final selector bank multiple, but owing to the connection of comparatively low resistance earth 20 through the upper winding of relay HA the circuit is effectively guarded against selection.

The calling circuit is now extended by way of the wipers negative 1, positive 1, $P1$ and $M1$ of the primary finder over resting armatures of relay HB and operated armatures of relay HA over the dotted connections at the distributing frame IDF to the associated first selector accessible over the bracketed conductors (Fig. 4). It may be however that both test wipers $P1$ and $P2$ will 30 encounter marking battery from different calling lines at the same instant, and in this case relay PA in operating will take precedence over relay PB since the locking circuit of the latter includes a resting contact of relay PA. Operation of the 35 calling subscriber's meter MTR in Fig. 1 is effected when the calling subscriber replies by the application of potential to the metering conductor M by the controlling switch in the train.

Upon the release of the connection when the 40 calling subscriber replaces his receiver, holding earth is removed from the release trunk conductor P by the controlling switch in the train, whereupon the relevant switching relay in the finder and the K relay in the line circuit release. The release of the switching relay in the 45 finder completes a self-interrupted driving circuit to the rotary magnet RM from earth connected to conductor 22 by way of common equipment arranged to give an alarm in case of failure. The release and the wipers are thereupon automatically rotated to the 12th position. In this 50 position the normal rotary springs $NR1$ restore and the supporting means for the shaft and wipers is mechanically tripped so that they fall 55 by gravity assisted by a spring and then rotate beneath the bank under the control of this spring to the full normal position. The construction of a two-directional switch arranged to restore to normal in the manner just described is given in 60 British Patent No. 391,123.

In the fully normal position the off-normal springs $N1$ and $N2$ again open, springs $N1$ disconnect low resistance earth by way of the right-hand winding of relay HB from the bank $R1$ of the distributor switch and replacing it by battery from the first group selector to mark the 65 finder as idle. Springs $N2$ open the self-interrupted driving circuit to the rotary magnet and the magnet ceases to function.

It will be appreciated from the circuit arrangement that the operation of the rotary magnet persists during the period that the wipers are 70 being restored vertically and moved to their normal position below the bank, and it is therefore 75 conveniently arranged that the rotary pawl is out

of engagement with the ratchet during this period. If the switch fails to release within a reasonable period, the continuous operation of the rotary magnet will result in the common release signal equipment functioning after a suitable period to give an alarm of the faulty condition.

If the calling subscriber should abandon the call during the finding operation, the start relay ST will release either due to the release of the level start relays SA to SE if armature $rs2$ is not operated, or due to the release of relay LK if armature $rs2$ is operated. It will be recollected that relay RS is operated when the calling level is found so that if the calling subscriber abandons the call before the calling level is found relay ST will release due to the release of the level start relays while if the calling subscriber abandons the call after the calling level is found relay ST will release due to the release of relay LK. Relay 20 LK in these circumstances is holding over its upper winding to marking battery connected over the vertical bank so that when the marking battery is removed due to the release of relay L then relays LK and ST will release. The release of relay ST causes the control set and the finder to restore to normal and it will thus be seen that whenever the calling subscriber hangs up his receiver the release of the finder immediately takes place.

Consideration will now be given to the case when all regular finders of the group in question are in use so that further calls will require to be extended over and overflow finder having access to a selector in the common group by way of a secondary finder such as SFS (Fig. 4). Owing to the fact that all the regular finders are in use negative marking battery will disappear from the common conductor 23 (Fig. 5) extending to the grid of the valve VAA whereupon the grid of this valve then becomes positive with respect to the filament and as the result of a substantial increase in the plate circuit current produced by this condition relay RFB connected in the plate circuit then operates. The device VAA is preferably a vacuum tube having three or more electrodes, but use may alternatively be made of a grid controlled gas discharge tube or the like. It will be understood that the metal rectifier MRA provided in each finder is connected up in such sense as to prevent the earth subsequently connected to the bank $R1$ of the distributor from shunting the idle marking battery of other finders connected to the same common conductor 23. Relay RFB in operating short-circuits relay RFZ which it will be remembered is normally operated in series with the filament of the valve VAA so that this relay releases. Relay RFZ at armature $rfz1$ completes the filament circuit to the other valve VAB by way of the various resistances shown, at armature $rfz2$ removes the short-circuit from the upper winding of relay OFC (Fig. 6) of primary control set PC1, at armatures $rfz3$ and $rfz4$ removes a similar short-circuit from relays OFC of primary control sets PC2 and PC3 shown diagrammatically as dotted rectangles, at armature $rfz5$ prepares a locking circuit for relay OFC of primary control set PC1, at armatures $rfz6$ and $rfz7$ prepares similar locking circuits for relays OFC in primary control sets PC2 and PC3 and at armature $rfz8$ (Fig. 9) connects up earth to operate relay OS. One relay such as OS is provided to every three secondary start groups such as SSI (Fig. 9) and controls in all 6 armatures, two of which are associated with each secondary 70 75 80 85 90 95 100 105 start group that is, one to each of the two control circuits associated with each secondary start group. One of the armatures only is shown, namely os_1 (Fig. 9) which on operation disconnects earth from the bank contacts of the overflow primary distributor OPD and replaces it with idle marking battery by way of the resistance YA connected in parallel with the upper winding of the start relay DS of secondary start group SS1. The other armature of relay OS associated with the secondary start group SS1 is located in the other secondary control circuit.

In case regular and overflow finders were connected to the same distributor switch, earth connected over resting contacts of relay OS would serve to mark the overflow as busy while regulars were still available.

Returning again to relay OFC in the primary control set PC1, it should be explained that although the short-circuit is removed from its upper winding this relay does not operate until the last regular finder has been fully set and the control relays are restored to normal. When this is done the driving magnet RPM of the regular primary distributor RPD is energized in the kick-on circuit to advance the wipers on to the next set of bank contacts, but as all regular finders are now in use testing wiper R1 will encounter earth in all positions of the bank and the pre-selecting control relay G thereupon immediately operates. Relay G at armature g_1 extends earth to the driving magnet RPM but as the armature r_2 has opened meanwhile, the circuit is completed via the upper winding of relay OFC which thereupon operates and is of sufficiently high resistance to prevent the operation of the magnet. Relay OFC thereupon locks on its lower winding by way of armature ofc_1 and in a parallel circuit operates the relief relay OFR.

It will be seen from the drawings that the operation of relays OFC and OFR at armatures ofc_2 , ofc_3 , ofc_4 , ofc_5 , ofc_6 , ofr_2 , ofr_3 , ofr_4 , ofr_5 and ofr_6 transfers the control leads extending from primary control set PC1 to the driving magnet and wipers of the overflow primary distributor OPD. Similar operations take place in primary control sets PC2 and PC3 so that their associated overflow primary distributors are connected in circuit and all subsequent calls in the group are thereupon completed over overflow finders.

For the purpose of the description, it will now be assumed that a further call is handled by primary control set PC1 and that the finder shown in Figs. 2 and 3 is one of the overflow group. It will also be understood that the connections shown in broken lines intercepted by dots will now apply. Relay ST is operated from the start circuit in the manner already described, and as the overflow primary distributor OPD is already standing in engagement with a free overflow finder, wiper O1 will pick up idle marking battery by way of the connections at the distributing frame to the resistance YA connected in parallel with start relay DS of the secondary start group SS1 (Fig. 9). Relay LK in the primary control set PC1 thereupon immediately operates and locks, relay DS also operates in this circuit. After a short period relay VR operates to prepare for the vertical operation of the finder in the manner previously described. Under the present circumstances, however, and owing to the different connections at the distributing frame, relay VR also at armature vr_3 extends direct earth over the wiper O1 of the

distributor to maintain the start circuit to relay DS in the secondary start group and also to busy this point of access to other hunting distributor switches. Earth at armature vr_3 also provides a locking circuit over the metal rectifier MRB for relays OFC and OFR which is effective in case a regular finder becomes free meanwhile and brings about the re-operation of relay RFZ. The metal rectifier MRB is included in this circuit so as to prevent earth from armature r_2 starting up the secondary control group prematurely.

It will be understood that the secondary start groups SS1 are accessible in common from the overflow primary distributor switches serving different groups of lines and are provided in numbers sufficient to cater for the maximum traffic on these groups of lines. It is also arranged that adjacent contacts in the banks of the distributor switches extend to different secondary start groups in order to increase the possible availability, although it is conceivable that the same secondary start group may make more than one appearance in the banks of a distributor switch but only on contacts which are widely spaced apart.

Returning again to the primary control set PC1 it will be seen that relay VR at armature vr_4 (Fig. 8) again connects up relay SF, but under these circumstances relay SF is not immediately operated and the resistance YA connected in parallel serves to connect up a marking battery to mark the overflow finder which has been taken into use in the bank multiple of the secondary finder switches SFS. From this point the operations of the overflow finder proceed as described for the regular finder and when the calling line is located one or other of the testing relays PA or PB in the primary control set operates to terminate the hunting operation. If the overflow finder taken into use is not yet found by one of the secondary finders SFS there will be no circuit for relay CO owing to the non-operation of relay SF and the control set therefore remains held in this condition.

It will be understood that simultaneously with the hunting operation of the overflow finder to find the calling line, two secondary finders such as SFS (Fig. 4) are set in operation to find the overflow finder which has been taken into use. These secondary finders have no normal resting position for their wipers and it will be appreciated therefore, that the arrangement of setting two in operation simultaneously considerably reduces the time taken to find the overflow finder.

Considering the detailed circuit operations, when the start relay DS is operated from the primary control set it locks over its armature ds_1 to the access point S2 and at armatures ds_3 and ds_5 completes a circuit to the control relays of the secondary distributor switch SED to cause this switch to select the first available secondary finder. A similar circuit is completed by way of armatures ds_4 and ds_6 to another secondary distributor (not shown) which also selects a further secondary finder. In order to still further reduce the finding time it is arranged that the secondary distributors perform a preselecting function which ensures that their wipers are automatically positioned into engagement with a free secondary finder if there is one available.

It will be seen from reference to the circuit that under normal conditions if the secondary finder engaged by the distributor is busy, the

test wiper SE_1 will encounter earth from armature sk_2 which is operated at this time, and this is extended through both windings of relay DK in series, comparatively low resistance 25 shunted by the high resistance relay DR and another resistance 26 , interrupter springs sem_1 , armatures ds_3 , sd_1 and fr_6 , winding of extremely high resistance relay $!G$ to battery. Owing to its high resistance, relay $!G$ is only operated in this circuit and at armature $!g_1$ energizes the driving magnet SEM of the distributor. The magnet SEM in energizing prepares for the advancement of the wipers SE_1 to SE_5 into engagement with the next set of bank contacts and at the conclusion of its stroke operates the associated interrupter springs sem_1 , thereupon opening the circuit to relay $!G$ which releases. In this manner interaction takes place between relay $!G$ and the magnet SEM so that the wipers are automatically stepped into engagement with a free secondary finder. It therefore follows that as soon as relay DS operates, both secondary distributors SED should switch through on to idle secondary finders but in order to obviate the possibility of incorrect operation owing to a disconnection in the bank engaged by wiper SE_1 it is arranged that when a call is initiated a test is made over this wiper for idle marking battery connected to the P wire by the associated group selector (not shown). If no such battery is encountered relay DK will fail to operate and the following self-interrupted driving circuit becomes effective to the magnet SEM to advance the wipers on to the next set of bank contacts; earth at armature ds_5 , armatures dk_1 and dr_3 , interrupter springs sem_1 , armature ds_3 , winding of the magnet SEM to battery. Automatic rotation therefore takes place and when an idle marking battery is found relay DK then operates over both its windings in series and opens the circuit of the magnet at the resting contacts of its armature dk_1 , while at the make contacts of this armature a circuit is completed to the holding winding of relay DK which is sufficiently low in resistance to mark the selected secondary finder as busy in the bank multiple of the distributor switches SED. The operation of armature dk_1 also disconnects the shunting resistance 25 from relay DR which thereupon proceeds to operate in series with the left-hand winding of relay DK which is shunted by the resistance 25 , to battery in series with the driving magnet SEM. It will be recognized that relays DK and DR present a similar combination to relays LK and VR in the primary control set and they are intended to perform an exactly similar function, namely the prevention of dual switching.

If it is assumed that no other secondary allotter SED is testing the same contact, relay DK will hold in spite of the opposition of its left-hand winding and after a short interval relay DR also operates. Relay DR locks by way of its armature dr_1 , at armature dr_2 disconnects the shunting resistance 26 at armature dr_3 opens a further point in the circuit to the magnet SEM, at armature dr_4 connects full earth to wiper SE_1 at the same time short-circuiting relay DK which releases, at armature dr_5 extends earth over wiper SE_5 to the negative conductor to prepare the associated group selector for operation, at armature dr_6 prepares the testing circuit to relay FK and at armature dr_7 extends earth over wiper SE_3 to energize the driving magnet SFM. The driving magnet of the secondary finder thereupon energizes in a self-interrupted circuit con-

trolled by the contacts sf_1 to rotate the wipers SF 1 to SF 4 in search of the overflow finder which has been taken into use. When this is found the test wiper SF 1 will pick up marking battery connected in parallel with relay SF in the primary control set which is extended over the bank and wiper SE_4 of the secondary distributor switch to energize relay FK over both its windings in series. Relay FK thereupon opens the circuit of the secondary finder magnet at the resting contacts of its armature fk_1 , while at the make contacts of this armature a circuit is completed to the upper holding winding of relay FK which is sufficiently low in resistance to mark the overflow finder selected as busy in the bank multiple of the secondary finder switches SF S . The operation of armature fk_1 also removes a shunt from relay FR which thereupon proceeds to operate in series with the lower winding of relay FK shunted by a resistance 27 to battery in series with the driving magnet SFM. Again the relays FK and FR are similar in function to relays DK and DR in that they guard against the dual switching of secondary finders on to the same overflow finder.

If it is assumed that no other secondary finder is testing on the same contacts at this instant, relay FK will hold in spite of the opposition of its lower winding and relay FR thereupon operates after a slight interval, thereby at armature fr_1 disconnecting the opposition winding to relay FK, at armature fr_2 supplements the earth to wiper SE_5 , at armature fr_3 opens the shunt about its own winding, and at armature fr_5 provides an alternative holding circuit to relay DR. Relay SF in the primary control set is operated in series with relay FK in the secondary distributor, and at armature sf_2 completes an operating circuit for relay CO which becomes immediately effective since it is assumed that the overflow finder has already found the calling line. Relay SF also at armature sf_1 opens the circuit to the start relay DS in the secondary start group and at the make contacts of this armature connects earth by way of the metal rectifier MRB to hold operated the changeover relay OFC and OFR for the purpose already described. Relay CO serves to release the primary control set and allow the overflow finder to switch through in the manner already described and when this is done the holding circuit to relay FK in the secondary distributor is opened and it releases. A circuit is thereupon completed at armature fk_1 for operating the switching relay SK in the secondary finder which locks by way of its armature sk_1 to earth connected to the release trunk conductor P from the associated group selector, at armature sk_2 connects guarding earth to the bank of the secondary distributor, and at armatures sk_3 to sk_6 extends the negative, positive, M and P leads through to the associated group selector.

The calling subscriber now receives dialling tone from the group selector and proceeds to set up the connection by operating his dial switch in the usual manner.

Relay $!G$ is operated from earth extended over the front contact of armature sk_1 , wiper SE_2 and armatures fr_4 and fr_6 ; and at armature $!g_1$ energizes the driving magnet SEM to prepare for the advancement of the wipers of the distributor switch on to the next set of contacts. Relay DR is short-circuited by earth connected up by armature $!g_1$ whereupon it releases and is followed shortly afterwards by relay FR which in turn

opens the circuit to relay **IG**. All relays in the secondary control group are therefore released and upon the de-energization of the magnet **SEM** the wipers are automatically stepped on to the next set of contacts.

Considering now the condition when the last overflow finder in the group is taken into use, negative battery will be removed from the common conductor **28** extending to the valve **VAB** (Fig. 5) whereupon the grid of this valve then becomes positive with respect to the filament and the increase in the plate current brought about by this condition results in the operation of relay **OFB**. Relay **OFB** at armature *ofb1* completes a circuit for relay **OFZ** which becomes effective when the last overflow finder has been fully set and the primary control set restores to normal. When this happens relay **VR** in the control set releases and at armature *vr1* removes a short-circuit from relay **OFZ** which immediately operates and at armatures *ofz1*, *ofz2* and *ofz3* transfers the start circuit for the various primary control sets to conductors **29**, **30** and **31** extending to overflow meters (not shown) individual to each set. Further calls during this condition are therefore registered on the particular overflow meter concerned. In case an overflow finder should become free meanwhile, the grid of the valve **VAB** will again become negative and as a result of the decrease in the plate current, relay **OFB** will release to open up access to the primary control sets.

Similarly, in case a regular finder should become free meanwhile, the grid of the valve **VAA** will become negative whereupon relay **RFB** releases to open up the primary control sets for access to the regular finder group.

If all secondary finders under the control of the start group **SS1** (Fig. 9) become busy, relay **OB** will release due to the removal of all idle battery connections from the common conductor **32**. Relay **FB** is operated from armature *ob1* and at armatures *fb1* and *fb2* opens the driving circuit to the respective secondary distributors to prevent useless hunting, and at armatures *fb3* and *fb4* extends earth to the access points **S1** and **S2** and disconnects the start relay **DS**.

In case the secondary start group shown should be the last in use prior to the busy condition, it will be seen that the release of armature *ob2* bridges both access points **S1** and **S2** to ensure that overflow finders connected to one access point are immediately busied in the banks of the distributor switches **OPD**, from the overflow finder in use connected to the other access point. It is conceivable that the condition may arise when all secondary finders in the exchange are in use at the same instant. This will have the effect of restoring all the **OB** relays in the exchange and consequently negative potential will be removed from the grid circuits of all valves **VAB** in the exchange whereupon the respective relays are operated to connect up the overflow meters and prevent access to the overflow finders.

As mentioned in the early part of the description relay **ST** (Fig. 6) in operating is arranged to connect up the delayed alarm changeover set which functions in case the primary control set is not freed within a predetermined period of time.

Considering now the operation of the changeover set in detail, relay **ST** in operating at armature *st5* extends earth over common conductor **33** which sets in operation a motor arranged to drive the cam assembly **34** which applies an earth

impulse to the **S** and **Z** conductors having a definite period of time between each application. When earth is applied to the **S** pulse conductor a circuit is completed for operating relay **TA** over its left-hand winding whereupon the relay locks on its right-hand winding by way of armature *ta1*, at armature *ta2* connects relay **TB** in circuit with the **Z** pulse conductor, and at armature *ta3* prepares a short-circuit to the left-hand winding of the start relay **ST**.

If the control equipment fails to release after the predetermined period has elapsed an impulse will be delivered over the **Z** pulse conductor which operates relay **TB** over its left-hand winding so that this relay then locks over its right-hand winding at armature *tb1*, to earth at resting armatures similar to *tb2* in primary control sets **PC2** and **PC3**. In parallel with this locking circuit an individual fault alarm lamp **LP** is lighted, at armature *tb2* earth is extended over conductor **35** to actuate an alarm associated with the particular rack upon which the equipment is mounted, at armature *tb3* earth is extended over another common conductor **36** to set in operation a main alarm which is common to the exchange, at armature *tb4* the short-circuit is removed from relay **TC** (Fig. 8) at armature *tb5* relay **LK** is released, at armature *tb6* the left-hand winding of the start relay **ST** is short-circuited and released and at armature *tb7* the start circuit is transferred to primary control set **PC3**. The primary control set **PC1** is thus released and switched out of service and further calls thereto are handled by primary control set **PC3**.

If, however, the primary control set has become associated with a finder, one or other of the relays **VR**, **RS** or **PA** will be operated and therefore when the short-circuit is removed from relay **TC** (Fig. 8) it immediately operates in series with relay **HA** in the finder. Relay **TC** locks by way of its armature *tc1*, at armature *tc2* extends earth to the test wiper **R1** of the distributor if relay **RS** has not operated to busy the finder against further selection, at armature *tc3* opens the circuit between relay **PA** and the test wiper **P1** of the finder since otherwise the operation of armature *rs1* would guard the line selected and prevent the subscriber from being served by other finders, at armature *tc4* releases relay **VR** and maintains relay **RS** if operated, at armature *tc5* (Fig. 8) opens the circuit to the rotary magnet of the finder, and at armature *tc6* (Fig. 6) provides a circuit for maintaining relay **OFF** in case a fault has occurred during overflow working. In this manner, therefore, the faulty circuit is locked as busy until the fault is cleared, whereupon the attendant will momentarily open the fault release link **FRL** (Fig. 6) to open the locking circuit of relay **TB** and restore the circuit to normal.

In case the regular first group selector is artificially busied for test purposes by the connection of earth to the release trunk conductor **P**, this earth will find a circuit by way of the resting off-normal springs **N1** in the finder to the testing bank **R1** of the distributor and therefore marks the associated finder as busy.

If the first group selector associated with a secondary finder is artificially busied for test purposes earth connected to the release trunk conductor **P** serves to busy the secondary finder concerned and also shunts the idle marking battery insofar as its function in holding relay **OB** is concerned, although it will be appreciated that owing to the presence of resistance **YA** in the cir- 75

cuit, relay OB will remain held from idle marking batteries of other idle secondary finders in the same group.

We claim:—

- 5 1. In a telephone system, calling lines having terminals arranged in groups, a finder switch having access to said terminals, said finder switch operated responsive to a call over one of said lines to step vertically to a group of said terminals 10 and then operated in a rotary direction to find the terminal of the calling line, and means for continuing the rotary movement in the same direction to initiate the release of the switch.
- 15 2. In a telephone system, calling lines having terminals arranged in groups, a finder switch having access to said terminals, a vertical and a rotary magnet for operating said switch responsive to a call over one of said lines, said vertical magnet operating the switch vertically to the 20 group of terminals in which the calling line is located, and said rotary magnet then operating the switch in a rotary direction to find the terminals of the line, and means for operating the rotary magnet again to initiate the release of 25 the switch, and a self-interrupted circuit for said rotary magnet over which the rotary magnet is operated in both movements.
- 30 3. In a telephone system, an automatic hunting switch, lines accessible thereto, said switch having movement in two directions to find one of said lines, a common apparatus for controlling the movement of said switch, magnets in the switch for operating the switch in said two directions, and means for operating one of the said magnets 35 to release the switch independent of the control by the common apparatus.
- 40 4. In a telephone system, a switch as claimed in claim 3 in which there is a self-interrupted circuit for said one magnet and means for operating said one magnet over said circuit both in the setting and release operations.

5 5. In a telephone system, a plurality of regular trunk circuits, a plurality of overflow trunk circuits, an electric discharge tube having a grid circuit, a source of potential in each of said regular circuits connected to said grid circuit, means in each of said regular circuits for varying the potential connected to the said grid circuit, and apparatus in the output circuit of said tube controlled by changes in all of said circuits connected to the input of the tube for rendering the overflow circuits effective. 10

6. In a telephone system, a plurality of circuits, an electric discharge tube, an input circuit for said tube connected to all of said circuits, means controlled over each circuit for disconnecting that circuit from the input of said tube, an output circuit for said tube, and apparatus in said output circuit operated when all of the circuits are disconnected from the input circuit of the tube. 15

7. In a telephone system, a plurality of switching devices, distributor switches operating to find an idle switching device, an electric discharge tube, means in each device for maintaining a potential on the grid of said tube as long as the devices are idle and for removing said potential when the devices are all busy, and means in the output circuit of said tube responsive to the removal of said potential for preventing the operation of said distributor switches. 25

8. In a telephone system, a group of regular finder switches and a group of overflow finder switches, an electric discharge tube, a lead from each regular finder to the grid of said tube, and means in the output circuit of said tube responsive to a change in potential in each of said leads for making the overflow finders available when all the regular finders are busy. 30 35
